UNITED STATES PATENT OFFICE

FREDERICK W. WATSON, OF CLEVELAND HEIGHTS, OHIO

BATTEN CLAMP

Application filed December 31, 1928. Serial No. 329,595.

This invention relates to tarpaulin clamping mechanism for hatches and particularly to battens and clamping means therefor for firmly clamping the edges of the tarpaulin about the combing of the hatch.

The object of the present invention is to provide tarpaulin clamping means for hatches whereby the battens are firmly held in place against the edges of the tarpaulin to hold it uniformly stretched in position over the hatch cover and prevent it from becoming dislodged.

In the embodiment herein shown the hatch combing is provided with a plurality of clamps forming stops and clamping means for battens which are adapted to engage the edges of the tarpaulin and clamping them neatly and firmly against the sides of the combing, the arrangement of the clamping means being such that the battens are forced downwardly and inwardly toward the combing and stops thereon to insure the proper positioning of the batten on the one hand and to insure a firm clamping means along substantially the upper edge of the batten for holding the tarpaulin in place.

The foregoing and other features of the invention will be brought out in the following description, drawings and claims.

Referring to the drawings, Fig. 1 is a sectional view through a hatch cover and combing illustrating the clamping and tarpaulin holding means; Fig. 2 is a front elevation; and Fig. 3 is a section.

In the arrangement shown 1 represents the hatch combing provided with the usual cover 2. The tarpaulin 3 extends over the cover and down the sides of the combing 1 and must be held in place along its edges against the outer face of the combing.

Secured to the outer face of the combing are a plurality of flanges 4 each carrying a threaded stud 5. These flanges also carry stop pads 6, there being two shown. These stop pads are symmetrically disposed on either side of the stud 5 and are preferably arranged just below the same as shown in Fig. 2. They form stops for the lower ends of the clamps as will appear. Engaging around each of the studs 5 is an elongated eye

7 forming the lower part of a batten hook comprising the shank 8 and a downwardly extending hook nose 9 adapted to engage the upper edge of the batten 10. The battens around the hatch are adapted to rest upon the stops formed by the upper straight edge of the flange 4, as shown in Fig. 2. Each of the clamps at the upper end of the eye and adjacent the shank 8 is provided with an arc-shaped tapered cam 11 adapted to engage the internal surface of a conical skirt 12 forming a part of a clamping nut 13 threaded onto one of the studs 5. This nut is provided with a suitable wrench or other hold 14.

In practice the tarpaulin is spread nicely over the cover with marginal portions extending down the sides of the cover about the hatch combing. The marginal portions are then drawn inward and engaged by the battens which are located in place back of the clamps, the hook portions 9 of the clamps engaging the upper edges of the battens. The operator then tightens all of the clamping nuts causing the batten clamps to be forced inward until the lower portions of the eyes 7 engage with the stop pads 6 when the upper ends of the clamps will be thrown inward toward the batten and the combing and continued rotation of the clamping nuts through the conical skirt and the cams 11 draw all of the hooks downward thus forcing the battens inward toward the combing and downward toward the stud flanges thereby firmly seating the battens in place against the tarpaulin and clamping it tightly against the hatch combing. In this way the tarpaulin is firmly held in place and cannot become loose at any point with obvious disastrous results, such as allowing wind to play havoc with the tarpaulin and otherwise producing an unsightly covering over the hatch.

Having described my invention, I claim:

1. In combination with a hatch combing, batten stop means arranged thereon, loose battens engaging the stop means and a plurality of batten clamps each having a single hook engaging the outer face and upper edge of the batten, clamp stop means for resisting the inward thrust of the clamps to force their upper ends toward said batten, and

means engaging said clamps and exerting inward and downward thrust thereon.

2. In a combined clamp and batten for hatch combings, a flange adapted to be secured to the combing and forming a lower stop for the batten, a clamping stud carried by said flange, stops carried by said flange below said stud, a clamp associated with said stud and having a portion extending below the same for engaging with the clamp stops and an upwardly extending single hook adapted to engage the outer face and the upper edge of the batten, a batten arranged between said hook and the flange, and means cooperating with said stud for exerting inward and downward thrust upon the clamp.

In testimony whereof I hereby affix my signature.

FREDERICK W. WATSON.
